[57] ABSTRACT

A kitchen hood ventilator comprising a casing including a warm air inlet, a cool air inlet, and an air outlet. A filter is mounted in the casing in the path of air flowing through the warm air inlet, and a cool air duct extends through the casing from the cool air inlet to a cool air outlet. The kitchen hood ventilator further includes a propeller fan for moving warm air through the filter and from moving cool air through the cool air duct. The propeller fan is driven by a fan motor mounted in the path of cool air flowing through the cool air duct. This permits the use of a relatively small motor that operates at substantially full power when rotating the propeller fan.

KITCHEN HOOD VENTILATOR

This invention relates to a kitchen hood ventilator of the type employed to remove cooking fumes and vapors from the cooling area of a kitchen, and more particularly to the control of the operating temperature of the motor of such a ventilator.

At the present time, various types of kitchen hood ventilators all in use. These include hoods in which the filter remains in the same position during use, hoods having a filter mounted in a slide-out drawer, etc. A problem common to all of the various types of kitchen hood ventilators is the operating temperature of the motor, which must be maintained at a relatively low level in order to comply with Underwriters Laboratories regulations.

The present invention comprises a kitchen hood ventilator including a cool air duct that extends from a cool air inlet to a cool air outlet. The fan motor of the kitchen hood ventilator is mounted in the cool air outlet of the cool air duct. The fan of the hood ventilator draws cool air through the duct and over the motor. This cools the motor and thereby permits the use of a relatively small motor that operates at substantially full capacity during the operation of the fan.

A more complete understanding of the invention may be had by referring to the following detailed description when taken in conjunction with the drawing, wherein:

FIG. 1 is a perspective view of a kitchen hood ventilator employing the present invention in which certain parts have been broken away more clearly to illustrate certain features of the invention, and

FIG. 2 is a sectional view of the kitchen hood ventilator shown in FIG. 1.

Referring now to the drawing, a kitchen hood ventilator 10 employing the present invention is shown. The ventilator 10 includes a casing 12 comprising a top wall 14, a front wall 16, a bottom wall 18, a rear wall 20 and a pair of opposed side walls 22 and 24. The casing 12 has a plurality of openings formed in it including a warm air inlet 26, a cool air inlet 28, and an air outlet 30. A door 32 is supported in the casing 12 for pivotal movement between the open position shown in the drawing and a closed position wherein the door 32 seals the warm air inlet 26.

The kitchen hood ventilator 10 further includes a dual filter unit 34 which is supported in the casing 12 by a filter bracket 36. The dual filter unit 34 preferably includes a shredded metal filament filter for the entrapment of grease and an activated charcoal filter for the removal of odors, but may include other conventional filters, if desired. The filter bracket 36 comprises a baffle that directs warm air entering the warm air inlet 26 into the dual filter unit 34.

A partition 38 extends through the casing 12 of the kitchen hood ventilator 10 from an opening 40 to the air outlet 30. A propeller fan 42 is mounted in the opening 40 and operates to move warm air into the warm air inlet 26, through the opening 40, through the space between the bracket 38 and the top wall 14, and out the air outlet 30. The propeller fan 42 is supported and driven by a fan motor 44 and is connected to the motor 44 by a shaft 46. The motor 44 is in turn driven by conventional 115 Volt, 60 Hertz line current, and is controlled by a suitable switch (not shown).

In accordance with the preferred embodiment of the invention, the fan motor 44 is a relatively small, relatively low output power motor that operates at substantially full capacity when driving the propeller fan 42.

5 Motors of this type normally operate at temperatures higher than the maximum operating temperature permitted by the regulations of the Underwriters Laboratories relating to kitchen hood ventilators. To this end, the kitchen hood ventilator 10 includes a cool air duct 10 48 which extends from the cool air inlet 28 along the rear wall 20 of the casing 12 and parallel the bottom wall 18 thereof to a cool air outlet 50. The propeller fan 42 of the ventilator 10 moves cool air through the cool air inlet 28, through the cool air duct 48, through the cool air outlet 50, over the fan motor 44, through the opening 40, through the space between the partition 38 and the top wall 14, and out the air outlet 30. The cool air flowing through the cool air duct 48 reduces the operating temperature of the fan motor 44 to an acceptable level and thereby permits the use of a relatively small, inexpensive motor in the kitchen hood ventilator 10.

In use, the kitchen hood ventilator 10 is mounted 25 over the cooking area of a kitchen so that the warm air inlet 26 receives warm air, fumes, odors, and the like from the cooking area. This positions the cool air inlet 28 of the filter unit 10 to receive relatively cool air from the kitchen cabinet positioned above the filter unit, through the kitchen wall mounted behind the filter unit, etc. Alternatively, the cool air inlet 28 may be connected to a suitable duct extending outside the kitchen.

The kitchen hood ventilator shown in the drawing 35 comprises a recirculating ventilator that returns air to a kitchen following the removal of grease, odors, etc. It will be understood, however, that the present invention can be employed in kitchen hood ventilators of the exhaust type. In the latter case, the propeller fan directs 40 air through an outlet form in the top wall of the casing and into a conventional exhaust duct.

From the foregoing, it will be understood that the present invention comprises a kitchen hood ventilator including a casing having a filter mounted in it. Warm 45 air is forced through the filter by a propeller fan that is driven by a small, low output power motor. A cool air duct mounted in the casing directs cool air over the motor and into the propeller fan. By this means, the operating temperature of the fan motor is reduced to 50 an acceptable level.

Although only one embodiment of the invention is illustrated in the drawing and described herein, it will be understood that the invention is not limited to the embodiment disclosed but is capable of rearrangement, modification and substitution of parts and elements 55 without departing from the spirit of the invention.

What is claimed is:

1. A kitchen hood ventilator comprising:
a casing including top and bottom walls, side walls, and a rear wall, and including a warm air inlet located adjacent the lower front corner, a cool air inlet located adjacent the upper rear corner, and an air outlet located adjacent the upper front corner;
a partition mounted in the casing and extending between an opening and the air outlet of the casing;

filter means mounted in the casing in the path of warm air flowing through the warm air inlet thereof;

a cool air duct mounted in the casing and extending from the cool air inlet downwardly along the rear wall of the casing and then parallel to and above the bottom wall of the casing to a cool air outlet;

a propeller fan mounted in the opening of the partition for moving warm air through the warm air inlet, the filter and the air outlet and for moving cool air through the cool air inlet, the cool air duct having predetermined load characteristics; and

a fan motor supported on the cool air duct in the cool air outlet thereof and therefore in the path of cool air flowing through the cool air duct under the action of the propeller fan, said motor for rotating the propeller fan and having predetermined output power characteristics,

the load characteristics of the propeller fan and the output power characteristics of the fan motor being so interrelated that substantially the full capacity of the fan motor is required to rotate the propeller fan.
